UNITED STATES PATENT OFFICE.

WILLIAM ELLIS HILL, OF PHILADELPHIA, PENNSYLVANIA, ASSIGNOR OF SEVEN TWENTY-FOURTHS TO FRANK H. BORDEN, OF PHILADELPHIA, PENNSYLVANIA.

REFRIGERATOR.,

Application filed March 10, 1926. Serial No. 93,730.

This invention relates to refrigerators.

The invention is applicable generally to the refrigerating art, but for purposes of illustration will be described and shown as applied to a refrigerating show case or display cabinet.

Some of the objects of my invention are: to provide a case of high efficiency; to provide a case in which disadvantageous dead air spaces are eliminated; to provide a case in which preserved materials are uniformly and efficiently cooled with a minimum consumption of ice or refrigerant; to provide a case in which the circulation of air is such that cooled air contacts with the wall of the case remote from the refrigerant; to provide a case in which the air current from the ice or refrigerant is divided to enhance the circulation through the case; to provide a case in which cooled air streams are caused to pass along two sides of a platter or material support; to provide a case in which removal of one or more trays carrying materials to be preserved has no appreciable effect upon the circulation in the case; to provide an improved circulatory method in a refrigerating case; to provide a case in which a plurality of cooled air streams are projected in stratas; and many other objects and advantages as will be apparent from the following description.

In carrying out the invention a case is provided in which the current of cooled air is divided into a plurality of streams and circulates in the case.

The invention is shown for purposes of illustration as embodied in a refrigerating show case, and in the accompanying drawings: Fig. 1, represents a vertical section through a show case in accordance with my invention, Fig. 2, is a similar section through a slightly modified form of show case indicating by long arrows the primary, and by short arrows, the secondary air streams, and Fig. 3 is a fragmentary diagrammatic view of a further slight modification of the invention.

Referring now to Fig. 1, the case comprises bottom wall 10, recessed as at 11, drained by convention trap drain 12. The case is provided with side or end walls 13, rear wall 14, icing lid 15, sliding doors 16, top 17, sight windows 18, supported by the front wall 20. All of the walls are insulated in any desired manner, and when so in-

sulated the point of attack for external heat is the sight windows, through which the heat passes with comparative ease. It is because the heat is really driven through the glass and a certain proportion of it contacts with materials on display and ruins such materials, that all other show cases of this description with which the public is acquainted, so far as known, fail in preserving the materials closest to the front of the case. This is largely due to faulty circulation permitting the formation of dead air pockets in proximity to the front of the tray carrying the displayed materials, and which this invention obviates, as will be more clearly seen as the description proceeds.

Accessible through the icing lid 15, is the ice or refrigerant supporting tray or support 21, preferably supported at the rear by legs such as 22, and upon which ice or a desired refrigerant or ice machine may be mounted. The tray 21 is perforated so that cooled air may pass through the tray from the refrigerant. In the present case, for illustrative purposes the refrigerant is shown as a block of ice 19, although any equivalents may be used.

Supported on the side walls or ends 13 is a guide means 30, shown as a solid baffle but which conceivably might be a series of shutters or some such arrangement, so arranged that there is a space or clearance between the upper end thereof and the case as at 8, and so that there is practically a similar space 9 between the bottom and the tray support 28, to be later described.

In the preferred form material tray supports are provided extending longitudinally of the case mounted on the end walls, as for instance as at 31 at the front of the case, and as at 28 toward the rear of the case. Support 31 is an angle iron, and support 28, comprises a stepped or off-set unit, in which the tray receiving shelf 24 terminates in an upstanding portion 27, which in turn is bent to form the horizontal tread 26 and vertical riser 23 of a diverting device, arranged to support the front edge of the ice tray 21, and to deflect or divert a certain portion of the cooled air stream falling through the ice tray, and to project it in a horizontal plane in spaced relation to the bottom wall of the case, just above the plane of the shelf portions of the material tray supports. It is to be noted that the

distance above the tray plane that the diverted or secondary air stream is projected is determined by the extent or width of the vertical or upstanding portion 27. This 5 width should be appreciable in order to space the secondary air stream from the primary air stream which falls from the refrigerant 19 to the bottom wall of the case, across the bottom to the front wall 10 20, then part passes upward against the inner face of the sight window for a slight distance while the other part bathes the front portion of the tray, when it curls or curves over toward the space 8 above the 15 guide or baffle 30, over the refrigerant and down again. In its course it will absorb such heat units as have been transmitted through the glass and thus eliminate any air pocket that might otherwise form toward the front portion of the case in proximity to the materials on the tray. This 20 action is facilitated tremendously by the secondary air stream which is projected from the tread section 26 through the space 9 25 under the baffle or guide 30 and travels across the case toward the front subjecting the materials on the tray to its influence, then curving or curling upwardly and back, merging with the primary air stream as it 30 passes over the upper end of the baffle 30.

As noted this plurality of circulatory air streams is maintained even with the material tray removed, and its action is of course the same with a tray in position as they are 35 then physically separated by a barrier, the tray, which is preferably solid and will not permit the passage of air through it. With the tray in position it will be observed that the bottom thereof is in contact with the primary air stream keeping the tray cooled, and simultaneously the upper surface of the tray and the materials displayed thereon are in contact with the secondary air 40 stream.

45 The case shown in Fig. 2 is practically the same, at least externally, as the case shown in Fig. 1. However there is a slight change that might be noted. It is desirable in some cases to provide a trough in connection with the diverting means to carry off the melted ice and similar matter, and therefore the diverter shown in the figure noted comprises a vertical fin 33 curving at the bottom to form the trough or gutter 34, 50 then upwardly again to form the projecting edge 35, across which the secondary air stream is drawn. For neatness and an attractive appearance, shutters 36 and 37 on the diverter 33 and baffle 38 respectively 55 may be applied to shield the contents of trough 34 and recess 12' from the eyes of an observer looking through the window 18'.

60 With this form of diverting means it is perfectly feasible to use the shutter 36 and

an angle iron, (not shown) to support a tray carrying the materials for display, yet a simpler device may be used, as shown in Fig. 2. This may comprise a perforated or longitudinally corrugated slatted rest 39, 70 mounted either directly upon the bottom wall 10', or upon short legs (not shown), and upon which the platter may rest.

The action in Fig. 2, is the same as in the other form of the invention, in which the cold air stream is divided the lower and colder primary stream passing along the bottom, to the front wall under the rest 37, where it curves up, some passing up the front wall and some curving back to bathe 75 the front of the tray in cold air, then up and over the baffle, while the secondary air stream is projected horizontally above the rest and bathes the materials on the tray with cold air, then it mixes or merges with 80 the primary circuit over the baffle.

Many applications of the principal involved will occur to those skilled in the refrigerating art, and all such should be considered as within the scope of the following claims, except where they may be otherwise limited.

I claim as my invention:—

1. A refrigerant case including a refrigerant support, a material support and means for directing cooled air on both sides of said material support.

2. A refrigerating case including a refrigerant support, a baffle adjacent the support over which warmed air passes, and means for directing a plurality of cooled streams of air under or beneath said baffle.

3. A case including a refrigerant support, guiding means adjacent the support over the upper portion of which an incoming air stream is arranged to pass, and means diverting a portion of the cooled air stream from its course below the support so that the diverted stream passes toward the opposite end of the case and then up with the incoming air stream.

4. A case including a refrigerant support, a material support below the level of the refrigerant support and spaced therefrom, and means for directing a layer of cooled air across the upper surface of said material support.

5. A case including a refrigerant support, a material support below the level of the refrigerant support and having a space beneath it, and means for providing a plurality of spaced air streams about said material support.

6. A case including a refrigerant support, a material support, and means for directing a plurality of cooled air streams in the same direction but in spaced planes from the plane of the material support.

7. A show case having a window in one wall, a refrigerant support toward an oppo-

site wall, a primary cooled air stream passing from the refrigerant support to the wall having the window, and a secondary cooled air stream passing from the support in spaced relation to the primary cooled air stream.

8. In a case the combination with a refrigerant support, of guiding means adjacent the support, and diverting means beneath the support, said means cooperating to divide the cooled air into a plurality of streams circulating in the case.

9. In a show case having a bottom wall, a refrigerant support mounted in the case adjacent one end of said bottom wall, a guide means adjacent the support, and a diverting element terminating in a projecting edge beneath and spaced from the guide means and arranged to direct a stream of cooled air across the case in substantial parallelism with but above the bottom wall.

10. In a show case having walls, a material supporting means above the bottom wall, a refrigerant support above the material supporting means, guiding means adjacent the refrigerant support the arrange-

ment providing a primary air stream from the support under the material supporting means to the front wall thence over the guiding means to the refrigerant support, 30 and means for maintaining a secondary air stream from the refrigerant support above the material supporting means toward the front wall which mixes with the primary air stream and passes over the guiding 35 means to the refrigerant support.

11. In a refrigerator, the combination with a rest for a platter, of a refrigerant, the refrigerator having a channel for the passage of a primary air stream from the 40 refrigerant on one side of the rest, with means from which a secondary air stream passes from the refrigerant on the other side of the plane of said rest.

12. A method of refrigerating which consists in bathing the bottom of a platter tray with a stream of cooled air, and simultaneously in bathing the upper portion of the tray with a stream of cooled air.

In testimony whereof I affix my signature:

WILLIAM E. HILL.
